UNITED STATES PATENT OFFICE.

WILLIAM McMEANS, OF WEST LIBERTY, IOWA.

MAUSOLEUM.

1,395,852.

Specification of Letters Patent.

Patented Nov. 1, 1921.

Application filed April 12, 1920. Serial No. 373,485.

To all whom it may concern:

Be it known that I, WILLIAM McMEANS, a citizen of the United States, residing at West Liberty, in the county of Muscatine 5 and State of Iowa, have invented certain new and useful Improvements in Mausoleums; and I do hereby declare the following to be a full, clear, and exact description of the invention, such as will enable others skilled 10 in the art to which it appertains to make and use the same.

This invention relates to certain improvements in what may be termed burial vaults.

The invention has for its object to provide 15 inclosing means for caskets, especially in excluding air or moisture therefrom.

A further object is to carry out the above purpose in an effective and simple manner and with facility.

20 Other objects of the invention will be apparent from the following description of the construction and operation of the device as hereinafter stated.

The invention, therefore, consists of certain 25 instrumentalities and features of construction substantially as hereinafter more fully disclosed and defined by the appended claims.

The accompanying drawings illustrate the 30 preferred embodiment of the invention or one example of carrying out the same, it being understood that various changes and modifications as to the detailed construction and arrangement of parts thereof may be 35 made without departing from the spirit or scope of my invention as covered by the claims.

In the drawings Figure 1 is a longitudinal section of my invention.

40 Fig. 2 is a horizontal section thereof, taken on the line 2, 2 of Fig. 1.

Fig. 3 is a transverse section of the same.

Fig. 4 is a reduced perspective view showing the inner inclosure with its closure removed and disposed relatively to the inclosure.

Fig. 5 is a fragmental representation of an adjunctive part of the outer inclosure and Fig. 6 is a fragmental sectional view of 50 the inner inclosure.

As characteristic features of my invention I provide an outer inclosure designated a 1 with its bottom edge seated in a continuous recess 3^a of a base member 3, the 55 outer lower edge of said outer inclosure being provided with a flange 4, said flange

having an upwardly facing recess 4^a. The bottom member 3 is provided, preferably, with a plurality of upstanding projections or extensions 5, the upper edges of which 60 are preferably notched or recessed as at 6 facing the bottom of an inner inclosure 7, said inner inclosure being supported upon said extensions or projections to suitably elevate said inner inclosure from the bottom 65 of the outer inclosure, said inner inclosure also being of less longitudinal and cross sectional area than the outer inclosure, thus providing an intermediate space 8 between the two inclosures to provide for the more 70 effective quarantining or spacing off the inclosed casket from moisture or air. The inner inclosure is provided with a closure 9 which is preferably rabbeted at its inner edge to receive the upper edge of the inclosure 7. The inner inclosure may be provided, as in Fig. 6, with a metallic ring as at 10 for aiding in effectively sealing the same air and moisture tight, said sealing ring being preferably arranged in coincident 75 concavities or recesses in the meeting edges of said closure, and somewhat nearer the inner edge of the latter, to prevent liability of displacement of the ring or gasket 80 in placing the closure in position thereon.

Referring more particularly to Fig. 3, it will be seen that I provide suitable means for lowering the outer inclosure in position within the excavation or grave by the use of clamping means, said clamping means comprising, preferably, flat bars 11 inserted under the member 3 and having upwardly extending terminals 11^a, provided with apertures 11^b. Pivoted to said upwardly extending terminals of the bars 11 are preferably 85 S-shaped levers 12, the outer ends of said levers being adapted to rest upon the ground or surface as when the outer closure is lowered into the excavation while the inner terminals of said levers are adapted to enter 90 the recess 4^a of the flange 4 of said inclosure as clearly shown in said figure, said levers being provided with extensions 13 having 100 apertures 13^a. It will, therefore, be seen that when the outer inclosure is lowered into 105 position upon the member 3 by means of cables 14, as also shown in Fig. 3, the levers as they contact with the surface will be brought into clamping position with the flanges 4 of the outer inclosure and thus prevent any liability of the pounding of said inclosure in lowering said inclosure into po- 110

sition. After said lowering of the outer inclosure it will be seen that by pulling on the cables 14 they may be readily removed, the clamping action of the levers 12 thus being utilized to retain the outer inclosure against inadvertent displacement or movement.

It will thus be seen from the foregoing description and explanation of my device that the same is readily utilized for its intended purpose and is highly desirable therefor.

The inner inclosure 7, it will also be observed, has a plurality of longitudinal grooves 7 in its bottom for the drainage of moisture from the casket, a suitable outlet 15 being provided for said drainage.

It will be understood that the several inclosures and the closure of the inner inclosure together with member 3 are preferably of pottery ware or other suitable material, and said inclosures and closure may be treated to a moisture-proofing coating, as a bi-product of petroleum, etc.

Having thus described my invention, I claim—

25 1. A device of the type described, including an outer inclosure, a bottom member having a recess therein adapted to receive the lower edge of said outer inclosure, a plate or bar having upwardly extending ter-

minals having apertures, and levers pivoted 30 to said terminals, said upwardly extending terminals, and said lever having eye-ended terminals to receive together with the apertures of the terminals of said bar cables for lowering the outer inclosure in position, a 35 terminal of said lever adapted to bear upon the surface of the ground as the outer inclosure is lowered into position upon the inner inclosure.

2. In a device of the type described, an 40 outer inclosure having a bottom flange, a bottom-member having said flange resting thereon, bar-members positioned under said bottom-member and having upwardly extending apertured terminals and levers pivoted 45 upon the upwardly extending terminals of said bar members, said levers having apertured extensions and adapted to engage the bottom-flange of said outer inclosure and to bear upon the surface of the ground, 50 said apertured extensions of the levers and said apertured terminals of the bar member adapted to provide for the application of means thereto for lowering the outer inclosure into position.

In testimony whereof, I affix my signature.

WILLIAM McMEANS.
